MACHINE FOR HEAT-TREATING STRIP MATERIAL

William E. Small, Hagerstown, Ind., assignor to Perfect Circle Corporation, Hagerstown, Ind., a corporation of Indiana

Application December 3, 1954, Serial No. 472,989

24 Claims. (Cl. 266—2.5)

The invention relates generally to heat treating apparatus and more particularly to a machine for heat treating and shaping partially preformed strip material.

In one form of piston ring assembly utilized in present day internal combustion engines, a combined spacer-expander member is provided to hold a pair of thin steel rails properly spaced from each other and in operative engagement with the cylinder wall. The spacer-expander member is made from a flat strip of sheet metal which is transversely punched alternately from opposite edges of the strip and is bent along longitudinal lines to provide a structure U-shape in cross-section. This structure is then formed into a circle and is adapted to be placed between the rails to hold them in spaced relation to each other. Flanges are provided on the ends of the arms of the U to engage the inner peripheries of the rails. When the ends of such a member are in abutment with each other, the slotting permits circumferential expansion and contraction, and with proper pitch length between the slots when the member is in its free state, the member will exert a predetermined outward force on the rails when the latter are confined within a cylinder. A piston ring assembly of this type is shown in the Shirk Patent No. 2,635,022, issued April 14, 1953, and the Estey Patent No. 2,695,825, issued November 30, 1954.

Piston rings have also been made, which have a construction similar in some respects to the spacer-expander member described above, that is, a ring which is transversely slotted to provide for circumferential expansion. It has also been suggested that circular springs for various uses be made in this manner.

The general object of the invention is to provide a novel machine for heat treating preformed strip material of transversely slotted type.

Another important object is to provide a novel machine for heat treating strip material of this type and to give the material a predetermined and uniform pitch length between slots.

A further object is to provide a novel machine of the foregoing character which may be adjusted to provide, within limits, any desired pitch length.

Still another object is to provide a machine of the foregoing character, which bends the material into a circular form while heated for the heat treating and which provides for quenching the material after it is given the proper pitch length and after bending into a circular form so that it has a permanent set in such shape.

A still further object is to provide a machine having the foregoing characteristics and which functions in a continuous manner so that the material may be fed to the machine in a long strip of indefinite length and the treated material comes off the machine in a continuously formed helical coil which may be separated into any desired lengths.

Other objects and advantages of the invention will become apparent from the subsequent detailed description

2

taken in conjunction with the accompanying drawings, in which:

Fig. 1 is an enlarged perspective view of a portion of the slotted strip material for which the present machine is adapted;

Fig. 2 is a perspective view of one embodiment of the invention;

Fig. 3 is a vertical sectional view taken on the line 3—3 of Fig. 2;

Fig. 4 is a sectional view taken on the line 4—4 of Fig. 3;

Fig. 5 is a fragmentary sectional view taken on the line 5—5 of Fig. 2;

Fig. 6 is a sectional view taken on the line 6—6 of Fig. 2;

Fig. 7 is a fragmentary rear view of the machine; and

Fig. 8 is an enlarged fragmentary sectional view taken on the line 8—8 of Fig. 6.

As heretofore mentioned, the machine or apparatus disclosed herein is adapted for heat treating transversely slotted strip material of the type utilized in certain piston ring assemblies or for piston rings themselves or for other purposes. To illustrate this type of material, I have shown in Fig. 1, as an example, a fragmentary portion 20 of a combined spacer-expander member constituting a part of a piston ring assembly of the character referred to. As is apparent in that figure, the member is formed from an elongated strip of sheet metal, which is transversely slotted alternately from opposite edges of the strip. This 25 slotting results in providing two rows of segments 10 along the respective edges of the strip, and the segments are connected by web members 11 which are spaced from each other and extend transversely of the strip. The strip is then bent along longitudinally extending lines into the 30 shape of a U in cross section with outwardly bent flanges 12 on the ends of the arms of the U.

After such slotting and bending, the strip is given a 35 circular form and is cut into individual members of a circumferential length needed for a cylinder in which it is to be used. A member of this construction is placed in a groove in a piston with the ends of the member in abutment and the pair of thin steel rails are then placed in the groove in operative relation with the spacer-expander member. When the piston with such a ring assembly is 40 placed in the cylinder of the engine, the rails are compressed from their free state, and the rails in turn cause a compression of the spacer-expander member from its free state, the web members 11 flexing edgewise when the member is compressed.

One function of this member is to exert an outward 45 expansive force on the rails to hold them in contact with the cylinder wall with a predetermined pressure. The expansive force exerted by this member will of course depend upon how much it is compressed from its free state. A member of this character may be said to have a pitch length which is the length of material between the side of one slot in one edge of the strip to the same side of the next slot in the same edge, and the member will be composed of a predetermined number of pitch 50 lengths for use in a cylinder of a given diameter. Since the circumferential length of the member in its free state is one of the factors determining the force it exerts on the rails when compressed within the cylinder, the pitch length for the strip must be carefully controlled in order to give the member, which has a predetermined number of pitch lengths, the correct circumferential length for its free state. The member must also be properly heat treated in order to give it the desired resiliency.

In making members of this character, the slotting and forming into the U-shape are performed on a continuous strip of a length sufficient to make a large number of members and the strip is then preferably wound on reels,

The reels are then taken to the heat treating machine embodying the features of the present invention, and the strip is unwound from the reel and fed continuously through this machine.

The machine or apparatus disclosed herein is arranged to heat the material to a desired temperature and to quench the material after such heating to give it the desired resilient characteristics. Preferably heating is effected by electrical induction means. When the material is so heated, it is in a sufficiently plastic state to permit it to be adjusted to the desired pitch length. The heated portion of the strip at any instant is of sufficient length to comprise a number of pitch lengths, so the adjustment is made on the total heated length. The strip comes from the slotting and bending operation with a certain pitch length. This may or may not be the desired pitch length for the member. While the desired pitch length may be less than that in the strip when it comes off the reels and the present machine may be employed to slightly decrease the pitch length, more accurate results and more satisfactory operation can be obtained if the pitch length of the strip before entering this machine is made slightly less than that desired and the strip is stretched, while undergoing heat treatment, to the desired pitch length in the machine.

The heating means of the present machine is tubular in form and the strip is moved continuously therethrough. To feed the strip through the heating means, if only a single feeding means located at the discharge end of the heating means were used, the pitch length could not be controlled since the drag due to unwinding the strip from the reel would vary and the strip would be variably stretched. To avoid this difficulty, a pair of feeding means is employed, one at the inlet end of the heating means and one at the discharge end. Each feeding means is provided with a toothed roll with the teeth engaging in the slots of the material to effect a positive feed thereof. The two toothed rolls are rotated at the same rate so that the length of material between them is thus held constant and the pitch length is thus maintained constant.

Since the material on the reel has a pitch length slightly less than desired, the length of the material between the two toothed rolls, which includes the heated portion, must be stretched. To this end, one of the feeding means is adjustable relative to the other to adjust the length of the material therebetween and thus give the material a predetermined pitch length. Thus, one feeding means may be shifted relative to the other to adjust the distance therebetween to adjust the length of the material between the two toothed rolls. The same effect may be obtained by rotating one of the toothed rolls slightly more or less than the other toothed roll. Thus, by imposing a slight counter rotation momentarily on the roll at the inlet end of the heating means, the number of pitch lengths between the two rolls will be slightly decreased and the material will thereby be stretched. In the present machine, the feeding means at the inlet end of the heating is shiftably mounted so that the distance thereof from the other feeding means can be adjusted, and this feeding means is so constructed that such adjustment also causes slight rotation of the toothed roll thereof counter to its normal direction of operation. Thus, adjustment of the pitch length is obtained by means which utilizes both types of adjustment of the feeding means.

The machine also includes as a part of the feeding means at the discharge end of the heating means a means for bending the material into circular form while it is still hot, and a means for spraying coolant onto the material so that the pitch length and the curvature of the material is permanently set. The material is then loosely wound in a helix and a helical coil of the material may be removed from the machine by breaking the strip at the desired point, the material being brittle after cooling.

The preferred embodiment of the invention, as illus-

trated in the drawings, comprises a frame in the form of a box-like cabinet structure indicated generally at 20 and shown in Figs. 1 and 2. Within the cabinet, there is provided a heating means which is tubular in character so that the material heated thereby may be continuously fed therethrough. As shown in Figs. 2 and 5, the heating element preferably is in the form of an induction heater and comprises a quartz tube 21 about which is wrapped a conductor 22 adapted to be connected to a source (not shown) of electrical current of suitable voltage. The heating means extends generally crosswise of the cabinet. The strip of material to be fed into the machine and through the heating means is preferably carried on a reel 19 at the left side of the machine as illustrated in Fig. 2, and the material enters the cabinet 20 through a guide tube 23 extending through an enlarged aperture 24 in the left wall of the cabinet and carried by a bracket 25 mounted on the exterior surface of the cabinet wall.

Because the material being treated is quite flexible and becomes quite plastic when heated, a single feeding means which would draw the material through the tubular heating means would be impractical because of the variable drag on the material in unwinding it from the reel. As generally discussed above, the pitch length of the material 20 has to be carefully controlled. For these reasons, a pair of feeding means are provided, one located at the inlet end of the heating means and indicated generally at 26 and the other located at the discharge end of the heating means and indicated generally at 27.

Both feeding means 26 and 27 are adapted to feed the material at the same rate so that the length of the material between the two feeding means, which includes the heated portion of the material, will be held constant. The material coming from the punching operation and carried on the reel may vary in pitch length to some extent. For this reason, the pitch length in the punching operation is preferably held less than is desired in the final form of the material, and the feeding means are arranged to stretch the material, while heated, to the desired pitch length. In order that the pitch length may be accurately controlled, one of the feeding means, in this instance the feeding means 26, is mounted for adjustment relative to the other feeding means 27.

In order that the two feeding means may feed the material at the same rate, a common drive means is provided therefor. Thus in the present instance, a motor 30 (see Fig. 7) is mounted within the cabinet 20 and is provided with a belt drive 31 connecting with a shaft 32 extending from feed means 27. The shaft 32 is connected through universal connections with a shaft 33 (see Fig. 2) for driving the feed means 26.

The feeding means 26 includes a housing 34 (see Figs. 2, 3, 4 and 7) mounted on a bracket 35 which is pivotally supported at its lower end by a rod 36 carried by the front and rear walls of the cabinet 20. The shaft 33 extends into the housing 34 at the rear end thereof and is journaled in bushings 37 mounted within the housing. Within the housing, a worm 40 is rigidly mounted on the shaft 33 and meshes with a worm wheel 41. The worm wheel 41 is mounted on the rear end of a stub shaft 42 journaled in bearings in the housing 34. The stub shaft 42 at its front end carries a toothed roll 43 (see Fig. 3) which engages the strip of material with the teeth thereof entering the slots in the material to positively feed the strip. The toothed roll 43 is preferably placed between two flange members 44 mounted on the shaft 42 and the toothed roll 43 and the flange members 44 are clamped thereon by means of a nut 45 threaded on the end of the stub shaft 42.

Cooperating with the toothed roll 43 is an idler roll 46 having a plain cylindrical periphery and mounted on a bearing 47 carried by a stud 50. The stud 50 is secured in an arm 51 extending downwardly from and adapted to be clamped on the front portion of the housing 34. Through the drive just described, the toothed roll 43 will

positively feed the strip of material to the heating means and draws the material through the guide tube 23. The left end of the quartz tube 21 is preferably supported in an opening 52 formed in a portion of the bracket 35, as shown in Fig. 2.

The feeding means 27 at the right or discharge end of the heating means is of generally similar construction and comprises a housing 53 carried on a bracket 54 rigidly mounted on the inside of the adjacent end wall of the cabinet 20. The shaft 32 extends into the housing 53 and has rigidly mounted thereon a worm 54 (see Fig. 6). The worm 54 meshes with a worm wheel 55 mounted on a stub shaft 56 extending forwardly in the housing 53 and journaled therein. At its forward end, the stub shaft 56 carries a toothed roll 57 which is of the same construction and size as the toothed roll 43 of the other feeding means. The toothed roll 57 is adapted to be clamped on the shaft 56 between a pair of flange members 60, and a nut 61 is threaded on the end of the shaft 56 to hold the toothed roll 57 and flange member 60 in fixed relation on the shaft.

The toothed roll 57 cooperates with a forming roll 62, which will be described more fully hereinafter, to draw the material from the heating means at the same rate that the feeding means 26 feeds the material into the feeding means. The forming roll 62 is journaled on bearings 63 mounted on a tube 64 clamped in a pair of arms 65, one at the front end of the housing 53 adjacent the toothed roll 57 and the other at the rear end of the housing. The arm 65 at the front end of the housing is clamped about the housing itself while the arm 65 at the rear end of the housing is clamped on a cover member 66 forming a part of the housing. With the foregoing structure, it will be apparent that both of the toothed rolls 43 and 57 are rotated at the same rate and thus feed the material at the same rate. The portion of the material between the two toothed rolls, which includes the heated portion of the material, will thus be held to a constant length.

As heretofore mentioned, the material fed to the present machine may vary in the pitch length thereof and preferably is made slightly less than that desired. The two feeding means which include the two toothed rolls 43 and 57, while holding the portion of the strip between them to a fixed length, can be relatively adjusted to adjust such length to that desired. For this purpose, the feeding means 26 is adapted to be adjusted relative to the feeding means 27, and while such adjustment can be in either direction, that is, either to compress or stretch the material, it is preferably arranged for such adjustment as will cause a stretching of the material while in the heated condition. The adjustment may be effected either by moving the feeding means 26 away from the feeding means 27 and thus causing a stretching of the material, or such stretching may be effected by rotatively adjusting the toothed roll 43 counter to its normal direction of rotation to decrease the amount of material between the two feeding means. In the present instance both forms of adjustment are simultaneously effected.

For this purpose, the bracket 35 is pivotally supported and may be swung on its pivot rod 36. To effect the swinging adjustment thereof, a nut 70 (see Figs. 2, 3 and 7) is pivoted at opposite sides thereof in a portion of the bracket 35 and an offset plate 71 secured to the bracket 35. Threaded in the nut 70 is a rod 72 which extends to the right within the cabinet 20 through the wall thereof and is fixed against endwise movement and provided with a knob 73 on its outer end. By rotating the knob 73, the nut 70 will be adjusted along the rod 72 to swing the bracket 35. When the bracket 35 is swung toward the left of the machine, the distance between the two feeding means 26 and 27 is thus increased and, since the toothed rolls thereof engage positively in slots in the material, the material therebetween will be stretched to the extent of such adjustment.

Adjustment of the pitch length of the material is also

effected by inducing a slight counter rotation to the toothed roll 43. To this end, the worm 40 is fixed on the shaft 33 and is permitted to have a slight movement relative to the housing when the bracket 35 is swung. Thus as shown in Fig. 4, a small space 74 is provided between the worm 40 and the bushing 37. When the bracket 35 is swung towards the left, the housing 34 also moves toward the left and carries the worm wheel 41 along with it. Since the worm 40 is fixed against endwise movement, a slight rolling movement of the worm wheel 41 is thereby effected along the worm 40. Such rolling movement of the worm wheel 41 is transmitted to the toothed roll 43 because they are both mounted on the same shaft, and the toothed roll 43 is therefore adjusted rotatively in a direction counter to its normal rotation in feeding the material. The counter rotation of the toothed roll 43 reduces the number of pitch lengths of the material between it and the other toothed roll 57 so that such rotative adjustment also effects stretching of the heated portion of the material. Thus adjustment of the feeding means 26 by the knob 73 both increases the spacing between the two feeding means and decreases the number of pitch lengths therebetween to effect the desired amount of stretching of the material. When the feeding means 26 is suitably adjusted, it is held in its adjusted position and the material continues to be fed thereby and the two feeding means thus hold the pitch length of the material to that desired.

The present machine also includes means for imparting a circular form to the material, the toothed roll 57 and the forming roll 62 performing this function. The forming roll 62, being carried by the arms 65 which are clamped about the housing 53, are adjustable about the axis of the toothed roll 57. To effect the circular forming of the material, the forming roll 62 is positioned so that the heated material as it leaves the quartz tube 21 of the heating means extends generally tangential to the forming roll 62, and the toothed roll 57 is so positioned that it causes the hot material to wrap over an arcuate portion of the forming roll 62. The material is thus bent into a circular form. The toothed roll 57 is therefore positioned to engage the material slightly beyond the point of tangency, as illustrated in Fig. 8. The forming roll 62 is driven at the same rate as the toothed roll 57 by means of a gear 80 mounted for rotation with the toothed roll 57 and meshing with a gear 81 secured to the forming roll 62, the gears 80 and 81 being of the same size. In order that the quartz tube 21 may be positioned so that the material emerging therefrom extends generally tangential to the forming roll 62 for any adjusted position of the latter, the quartz tube is supported in an L-shaped block 72 mounted on a plate 83 secured to a bracket having a hub portion 84 (see Fig. 6) adjustably mounted on the tube 64 which supports the forming roll 62. Thus when the forming roll 62 is adjusted about the axis of the toothed roll 57, the bracket supporting the quartz tube of the heating means may also be suitably adjusted about the axis of the forming roll 62. A strap 88 secured to the plate 83 and to the cabinet is provided to hold the plate 83 in its adjusted position.

The material, after it has been stretched to the desired pitch length and after it has been given the circular form by being wrapped partially on the forming roll 62, is then quenched to set it permanently in such condition. To this end a nozzle 85 (see Figs. 2 and 8) is provided and is connected to a means (not shown) for supplying coolant thereto. The nozzle 85 directs the coolant on to the material at substantially the point where the material enters the bite between the toothed roll 57 and the forming roll 62 and after the material has been given its circular form by being wrapped on the forming roll. The material is thus permanently set in the desired condition.

To prevent a pool of coolant from building up in front of the bite between the toothed roll 57 and the forming roll 62, which would tend to cool the material before it is given this circular form, the flange members 60 adjacent

the toothed roll 57 are provided with peripherally formed drain grooves 93 which will carry off any excess of coolant and prevent any pool from being formed at this point. It will also be noted that the heating means and particularly the quartz tube 21 slants downwardly toward the feeding means 27 where the coolant nozzle 85 is located so that there will be no chance of coolant running backwardly along the material where it would prematurely chill the material or run into the tube 21.

To facilitate handling of the material after it leaves the present machine, it is preferably formed into elongated helical coils. To this end a cam plate 86 (see Figs. 2 and 5) is secured to the block 82 which supports the quartz tube 21 and embraces the forming roll 62 immediately in front of the position where the toothed roll 57 and the forming roll 62 engage the material. On its free end, the cam plate 86 is provided with a lip 87 bent out of the plane of the plate so that the strip of material after being formed is forced longitudinally of the forming roll 62. Since the forming roll 62 is rotatably driven, the material coming off the machine will be formed into a helical coil on the forming roll. To support such coil, the forming roll 62 is elongated by being provided with an extension 90. To prevent the coil of material from binding on the extension 90, the latter is of reduced diameter relative to the forming portion of the forming roll, and the forming roll is tapered as at 91 to the diameter of the extension 90.

The material as it comes from the machine is quite brittle because of the heating and subsequent quenching. Thus when a helical coil of desired length of the material is formed on the extension 90, the inner end may be readily broken by merely snapping the material and the coil may be removed endwise from the extension 90 to permit another coil to be formed thereon.

From the foregoing description, it will be apparent that I have provided a novel machine for heat-treating preformed strip material of the transversely slotted type. By adjustment of the feeding means 26, the heated portion of the strip as it passes through the machine may be given a predetermined and uniform pitch length between slots. As the material emerges from the heating means, it is bent into a circular form and then quenched so that the material is permanently set with the proper pitch length and in its circular form. The machine operates in a continuous manner so that the material in large lengths may be fed thereto, and the treated material comes off the machine in a continuously formed helical coil which may be separated into any length suitable for handling.

I claim:

1. A heat treating machine for slotted strip material of the character described, comprising tubular induction heating means for heating the material as it is fed therethrough, a pair of feeding means located at the respective ends of said heating means for feeding the material into and withdrawing the material from said heating means to hold the heated portion of the material within said heating means to a predetermined length, and means for bending the material into circular form while still hot after passing through said heating means.

2. A heat treating machine for slotted strip material of the character described, comprising tubular heating means for heating the material as it is fed therethrough, a pair of feeding means located at the respective ends of said heating means for feeding the material into and withdrawing the material from said heating means to hold the heated portion of the material within said heating means to a predetermined length, means cooperating with the feeding means at the discharge end of said heating means for bending the material into circular form while still hot from passing through said heating means, and means for directing coolant on the material after being bent for giving the material a permanent set in its circular form and of predetermined unit length.

3. A heat treating machine for slotted strip material of the character described, comprising tubular heating means for heating the material as it is fed therethrough, and a pair of feeding means located at the respective ends of said heating means for feeding the material into and withdrawing the material from said heating means, said pair of feeding means operating at the same rate to hold the heated portion of the material to a predetermined length.

4. A heat treating machine for slotted strip material of the character described, comprising tubular heating means for heating the material as it is fed therethrough, and a pair of feeding means located at the respective ends of said heating means for feeding the material into and withdrawing the material from said heating means, each of said feeding means including a toothed roll with the teeth adapted to enter the slots in the material to positively feed the material, and means for driving the toothed rolls of both feeding means at the same rate to hold the heated portion of the material to a predetermined length.

5. A heat treating machine for slotted strip material of the character described, comprising tubular heating means for heating the material as it is fed therethrough, and a pair of feeding means located at the respective ends of said heating means for feeding the material into and withdrawing the material from said heating means at the same rate to hold the heated portion of the material to a predetermined length, and means for adjusting the spacing of one feeding means from the other to adjust the length to which the heated portion is held.

6. A heat treating machine for slotted strip material of the character described, comprising tubular heating means for heating the material as it is fed therethrough, and a pair of feeding means located at the respective ends of said heating means for feeding the material into and withdrawing the material from said heating means, a shiftable bracket supporting one of said feeding means, adjustable means for shifting said bracket for adjusting the spacing between said feeding means, and means for driving both of said feeding means at the same rate to hold the heated portion of the material to a length determined by said adjusting means.

7. A heat treating machine for slotted strip material of the character described, comprising tubular heating means for heating the material as it is fed therethrough, and a pair of feeding means located at the respective ends of said heating means for feeding the material into and withdrawing the material from said heating means, each of said feeding means including a toothed roll with the teeth adapted to enter the slots in the material to positively feed the material, means for adjusting the spacing of one toothed roll from the other, and means for driving both of said toothed rolls at the same rate to hold the heated portion of the material to a length determined by said adjusting means.

8. A heat treating machine for slotted material of the character described, comprising tubular heating means for heating the material as it is fed therethrough, and a pair of feeding means located at the respective ends of said heating means for feeding the material into and withdrawing the material from said heating means, each of said feeding means including a toothed roll with the teeth adapted to enter the slots in the material, means for driving the toothed rolls of both feeding means at the same rate to hold the heated portion of the material to a predetermined length, and means rotatively adjusting one of said rolls relative to the other to adjust the length of the heated portion.

9. A heat treating machine for slotted material of the character described, comprising tubular heating means for heating the material as it is fed therethrough, a pair of feeding means located at the respective ends of said heating means for feeding the material into and withdrawing the material from said heating means, each of said feeding means including a toothed roll with the

teeth adapted to enter the slots in the material, means for driving the toothed rolls of both feeding means at the same rate to hold the heated portion of the material to a predetermined length, and means for shifting one of said rolls relative to the other to vary the space between said rolls and for rotatively adjusting said one roll relative to the other to adjust the length of the heated portion.

10. A heat treating machine for slotted strip material of the character described, comprising tubular heating means for heating the material as it is fed therethrough, a pair of feeding means located at the respective ends of said heating means for feeding the material into and withdrawing the material from said heating means, and means for adjusting one of said feeding means relative to the other to adjust the length to which the heated portion is held.

11. A heat treating machine for slotted strip material of the character described, comprising tubular heating means for heating the material as it is fed therethrough, a pair of feeding means located at the respective ends of said heating means for feeding the material into and withdrawing the material from said heating means, and means for increasing the spacing of one feeding means from the other to stretch the heated portion of the material to a predetermined length.

12. A heat treating machine for slotted material of the character described, comprising tubular heating means for heating the material as it is fed therethrough, a pair of feeding means located at the respective ends of said heating means for feeding the material into and withdrawing the material from said heating means, each of said feeding means including a toothed roll with the teeth adapted to enter the slots in the material, means for driving the toothed rolls of both feeding means at the same rate to hold the heated portion of the material to a predetermined length, and means for shifting one roll away from the other and simultaneously rotatively adjusting said one roll to stretch the heated portion of the material to a predetermined length.

13. A heat treating machine for slotted material of the character described, comprising tubular heating means for heating the material as it is fed therethrough, a pair of feeding means located at the respective ends of said heating means for feeding the material into and withdrawing the material from said heating means, one of said feeding means comprising a toothed roll with the teeth adapted to engage in the slots in the material, a shiftable mounted housing enclosing a driven shaft having said toothed roll and a worm wheel mounted thereon, a drive shaft extending into said housing in slidable relation therein and having a worm rigidly mounted thereon in mesh with said worm wheel, and means for shifting said housing to adjust the spacing of said toothed roll from the other feeding means and to effect rolling movement of the worm wheel relative to the worm to rotatively adjust said toothed roll to adjust the length of the heated portion of the material, the other feeding comprising a toothed roll, and means connecting said last-mentioned toothed roll to said drive shaft for driving said last-mentioned toothed roll at the same rate as said first-mentioned roll.

14. A heat treating machine for slotted material of the character described, comprising tubular heating means for heating the material as it is fed therethrough, a pair of feeding means located at the respective ends of said heating means for feeding the material into and withdrawing the material from said heating means, each of said feeding means including a toothed roll with the teeth adapted to enter the slots in the material, a worm wheel element coaxial with one of said toothed rolls and drivingly connected thereto, a worm element for driving said worm wheel element, means for driving said worm element and the other toothed roll, and means for adjusting one of said elements longitudinally of the worm

element to rotatively adjust said one toothed roll relative to the other toothed roll to adjust the length of the heated portion of the material.

15. A heat treating machine for slotted material of the character described, comprising tubular heating means for heating the material as it is fed therethrough, a pair of feeding means located at the respective ends of said heating means for feeding the material into and withdrawing the material from said heating means, each of said feeding means including a toothed roll with the teeth adapted to enter the slots in the material, a worm wheel coaxial with one of said toothed rolls and drivingly connected thereto, a worm for driving said worm wheel, means for driving said worm and the other toothed roll, a support for said one toothed roll and said worm wheel, and means for shifting said support to roll said worm wheel along said worm and thereby rotatively adjust said one toothed roll to adjust the length of the heated portion of the material.

16. A heat treating machine for slotted strip material of the character described, comprising tubular heating means for heating the material as it is fed therethrough, and feeding means located at the discharge end of said heating means comprising a feeding roll and a forming roll holding the material therebetween to draw it from said heating means, said feeding roll being positioned to bend the material on the curvature of the forming roll while the material is still heated from the heating means.

17. A heat treating machine for slotted strip material of the character described, comprising tubular heating means for heating the material as it is fed therethrough, and feeding means located at the discharge end of said heating means comprising a feeding roll and a forming roll holding the material therebetween to draw it from said heating means, said feeding roll being located at a point beyond the point where the material first contacts said forming roll and holding the material against the forming roll to bend it to the curvature of the forming roll while the material is still hot.

18. A heat treating machine for slotted strip material of the character described, comprising tubular heating means for heating the material as it is fed therethrough, and feeding means located at the discharge end of said heating means comprising a feeding roll and a forming roll holding the material therebetween to draw it from said heating means, said forming roll being positioned so that the path of travel of the material through the heating means is generally tangent to the forming roll, said feeding roll being located beyond the point of tangency to bend the material to the curvature of the forming roll while still hot.

19. A heat treating machine for slotted strip material of the character described, comprising tubular heating means for heating the material as it is fed therethrough, and feeding means located at the discharge end of said heating means comprising a feeding roll and a forming roll holding the material therebetween to draw it from said heating means, said feeding roll being positioned to wrap the material around an arcuate portion of the forming roll to bend the material while hot, and means for directing a stream of coolant on the material after being bent.

20. A heat treating machine for slotted strip material of the character described, comprising tubular heating means for heating the material as it is fed therethrough, and feeding means located at the discharge end of said heating means comprising a feeding roll and a forming roll holding the material therebetween to draw it from said heating means, said feeding roll being positioned to wrap the material around an arcuate portion of the forming roll to bend the material while hot, and means for directing a stream of coolant on the material after being bent, said heating means slanting downwardly toward said forming

roll to prevent the coolant from running along the material toward the heating means.

21. A heat treating machine for slotted strip material of the character described, comprising tubular heating means for heating the material as it is fed therethrough, and feeding means located at the discharge end of said heating means comprising a feeding roll and a forming roll holding the material therebetween, to draw it from said heating means, said feeding roll being positioned to hold the material against the forming roll for an arcuate portion of the latter, said forming roll being supported for swinging movement about the axis of said feeding roll for adjusting the length of said arcuate portion, and means for driving both of said rolls at the same speed.

22. A heat treating machine for slotted strip material of the character described, comprising tubular heating means for heating the material as it is fed therethrough, and feeding means located at the discharge end of said heating means comprising a feeding roll and a forming roll holding the material therebetween to draw it from said heating means, said feeding roll being positioned to hold the material wrapped against the forming roll for an arcuate portion of the latter to form the material into a coil, and means for camming the material into a helix after it passes said feeding roll, said forming roll being elongated to receive the helix of material.

23. A heat treating machine for slotted strip material of the character described, comprising tubular heating 30

means for heating the material as it is fed therethrough, and feeding means located at the discharge end of said heating means comprising a feeding roll and a forming roll holding the material therebetween to draw it from said heating means, said feeding roll being positioned to hold the material wrapped against the forming roll for an arcuate portion of the latter to form the material into a coil, and means for camming the material into a helix after it passes said feeding roll, said forming roll being elongated and of reduced diameter beyond the forming portion thereof to loosely receive and support the helix of material.

24. A heat treating machine for slotted strip material of the character described, comprising tubular heating 15 means for heating the material as it is fed therethrough, and feeding means located at the discharge end of said heating means comprising a feeding roll and a forming roll for holding the material therebetween to draw it from said heating means, said feeding roll being positioned 20 to hold the material against the forming roll for an arcuate portion of the latter, a support for said forming roll mounted for swinging movement about the axis of said feeding roll for adjusting the length of said arcuate portion and a bracket on said support carrying the adjacent end of said heating means and swingable with 25 said support to adjust the end of said heating means to the adjusted position of said forming roll.
